(57) **CLAIM**

I claim the ornamental design for a base shoe for railings, as shown and described.

DESCRIPTION

FIG. 1 is a perspective view of the base shoe for railings showing my new design;

FIG. 2 is a right elevation view thereof;

FIG. 3 is a left elevation view thereof;

FIG. 4 is a front elevation view thereof;

FIG. 5 is a rear elevation thereof;

FIG. 6 is a top plan view thereof; and,

FIG. 7 is a bottom plan view thereof.

The broken lines in the figure drawings represent unclaimed environment only and form no part of the claimed design.
